US00D950505S

(12) **United States Design Patent** (10) **Patent No.:** **US D950,505 S**
Chuang et al. (45) **Date of Patent:** **** May 3, 2022**

(54) **SWITCHING DEVICE**

(71) Applicants: **Interface Technology (ChengDu) Co., Ltd.**, Sichuan (CN); **Interface Optoelectronics (ShenZhen) Co., Ltd.**, Guangdong (CN); **General Interface Solution Limited**, Miaoli County (TW)

(72) Inventors: **Fu-Chiang Chuang**, Miaoli County (TW); **Wen-Hsiao Huang**, Miaoli County (TW); **Fu-Cheng Wei**, Miaoli County (TW); **Chih-Lin Liao**, Miaoli County (TW)

(73) Assignees: **INTERFACE TECHNOLOGY (CHENGDU) CO., LTD.**, Chengdu (CN); **INTERFACE OPTOELECTRONICS (SHENZHEN) CO., LTD.**, Shenzhen (CN); **GENERAL INTERFACE SOLUTION LIMITED**, Miaoli County (TW)

(**) Term: **15 Years**

(21) Appl. No.: **29/813,238**

(22) Filed: **Oct. 27, 2021**

Related U.S. Application Data

(62) Division of application No. 29/708,087, filed on Oct. 3, 2019, now Pat. No. Des. 941,784.

(57)

CLAIM

The ornamental design for a switching device, as shown and described.

DESCRIPTION

FIG. 1 is a perspective view of the switching device;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom view of FIG. 1.

1 Claim, 7 Drawing Sheets
